DESIGN FOR A DUPLICATING MACHINE OR SIMILAR ARTICLE

William Ward Davidson, Evanston, and Harry S. Scholl, Glen Ellyn, Ill.; said Scholl assignor to Davidson Manufacturing Corporation, Chicago, Ill., a corporation of Illinois

Application April 3, 1941, Serial No. 160,117

Term of patent 14 years

To all whom it may concern:

Be it known that we, William Ward Davidson and Harry S. Scholl, citizens of the United States of America and residents of Evanston, county of Cook, and State of Illinois, and Glen Ellyn, county of Du Page, and State of Illinois, respectively, have invented a new, original, and ornamental Design for a Duplicating Machine or Similar Article, of which the following is a specification, reference being had to the accompanying drawings, forming a part thereof, wherein

Fig. 1 is a perspective view showing a duplicating machine embodying our design;

Fig. 2 is a right elevational view thereof on a smaller scale;

Fig. 3 is a rear elevational view thereof on the smaller scale; and

Fig. 4 is a left elevational view thereof on the smaller scale.

What we claim is:

The ornamental design for a duplicating machine or similar article, substantially as shown.

WILLIAM WARD DAVIDSON.
HARRY S. SCHOLL.
